Primary Examiner — Martie K Holtje

(74) Attorney, Agent, or Firm — Arent Fox LLP

(57) **CLAIM**

The ornamental design for a combined toy and bag, as shown and described.

DESCRIPTION

FIG. 1 is a front perspective view of a combined toy and bag showing the new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a rear elevational view of the toy unzipped showing a portion of the bag;

FIG. 9 is a front elevational view showing the bag portion in a partially expanded condition;

FIG. 10 is a front perspective view showing the bag in a fully expanded condition;

FIG. 11 is a left side elevational view of FIG. 10;

FIG. 12 is a right side elevational view of FIG. 10;

FIG. 13 is a front elevational view of FIG. 10;

FIG. 14 is a rear elevational view of FIG. 10;

FIG. 15 is a top plan view of FIG. 10; and,

FIG. 16 is a bottom plan view of FIG. 10.
